UNITED STATES PATENT OFFICE

2,536,529

METHOD OF PRODUCING BAGS WITH
OPENING MEANS

Samuel Bergstein, Cincinnati, Ohio, assignor to
Robert Morris Bergstein and Frank David
Bergstein, trustees

Application August 9, 1944, Serial No. 548,652

4 Claims. (Cl. 93—35)

1

The invention relates to the problem of facilitating the removal of the contents of a bag or liner by the user. Its principal object has to do with the provision of means for the ready removal of the liner closure or seal, in whole or in part.

Another object of the invention is the attainment of the objective just mentioned, while retaining the integral nature of the bag or liner, so that its protective characteristics are not sacrificed. Yet another object is the provision of a method whereby such liners or bags may be made conveniently and inexpensively, as hereinafter set forth.

My invention is particularly adapted for use in connection with lined containers such as are shown in the Robert M. Bergstein Patents 2,099,257, of November 16, 1937, and 2,250,249, of July 22, 1941, made by the methods disclosed in Reissue Patent No. 20,789, of July 12, 1938, and by mechanisms such as are shown in Patent 2,114,621, April 19, 1938, and Patent 2,166,388, of July 18, 1939. However, the invention is not limited to any particular types of lined containers, but is equally suited for use with other types or for use with separate bags as such, as will become apparent as the description proceeds.

These and other objects of my invention, which will be set forth hereinafter or will be apparent to one skilled in the art upon reading these specifications, I accomplish in that construction and arrangement of parts and in that procedure, of which I shall now describe exemplary embodiments.

Referring to the drawings:

Figure 1 is a diagrammatic plan view of a section of one form of bag machine, showing the devices for performing my invention incorporated therein.

Figure 2 shows a section of a bag machine with an alternate form of my device incorporated therein.

Figure 3 is a partial sectional view taken along the line 3—3 of Figure 1.

Figure 4 is a partial sectional view taken along the line 4—4 of Figure 1.

Figure 5 is a partial sectional view taken along the line 5—5 of Figure 2.

Figure 6 shows a bag prepared in accordance with my invention imposed on a carton blank as taught in Patent 2,250,249.

Figure 7 is the flat, prelined carton of the type shown in Patent 2,250,249 previously mentioned, but embodying my invention.

Figure 8 shows a container, such as illustrated

2

in Figure 7, after it has been set up, filled, sealed, shipped and partially opened by the user, that is, the top flaps have been folded back into open position, exposing the sealed liner, which now must be opened.

Figures 9, 10 and 11 illustrate steps in the operation of removing the sealed end of the liner in accordance with the present invention.

Figures 12, 13 and 14 are a similar series of views showing the operation of opening the liner, when the liner has been treated as hereinafter explained in connection with Figure 2.

Briefly, in the practice of my invention, I have found that its objects may be attained by forming a predetermined line of weakening in the walls of a bag or liner so that they will tear readily along the predetermined line, and then coating said weakened line including a contiguous area of the bag walls with a film-forming substance capable of bonding tightly with the said walls and capable of filling or closing perforations in the weakened line, or forming a tenacious membrane thereover, thus preserving the proofness of the bag walls in spite of the line of weakening. The line or lines of weakening may be configured as hereinafter set forth. They may be continuous so as completely to define a line for severance; or, in materials hard to tear at a folded edge but readily torn after initial severance, they may merely be located to start a line of tear. The applied film will be such that it will sever along the weakened lines in the base web or bag wall. The film may be colored to call attention to the line or lines of weakening.

35 In Figure 1 is shown a section of a bag machine into which section unit length tubes are being delivered at the left hand end of the drawing from a tubing device (not shown). As they enter the illustrated machine section, the cut-to-length tubes are picked up by lugs 57 on the chains 56, and so are carried in timed relation to positively driven, frictionally surfaced upper and lower belts 58 which continue to carry the tubes in timed relationship. During their course 40 of travel, the tubes may be closed at one end to form bags, either by folding or sealing or otherwise, as described in Patent 2,114,621 previously mentioned.

The mechanism for performing the present invention is additive to the other mechanism and comprises a perforating roll 59. This roll is mounted on a shaft 60 having bearings on the side frames of the machine. The perforating roll operates against a lower anvil roll 61 mounted on a shaft 62 similarly journaled. Both shafts

will be driven from the machine drive in such a way that the peripheral speed of the rolls will match the speed of travel of the bag tubes as moved by the conveyor means 58.

In the embodiment shown, the roll 59 produces a line of weakening extending entirely across the bag tube near one of its ends and operates to form coinciding lines of weakening in both walls of the flattened tube. The form of the lines of weakening is not a limitation on my invention and may be considerably modified, particularly in view of the nature of the material from which the bag tubes are made. In thick and heavy materials, it is sometimes possible to weaken them by cutting them part way through their thickness. The type of weakening which I prefer is provided by making slits of short length or tiny perforations, closely spaced in the material. These slits are largely self-closing, so that when the subsequent coating material is applied, it will not strike through the slits to such an extent as either to adhere the walls of the bag together strongly or to become disintegrated and, therefore, no longer gas or liquid tight when the bag is forcibly opened as in filling.

Having been provided with a line or lines of weakening as aforesaid, the bag tubes are next carried by means of the conveyor 58 to a device which applies over the lines of weakening a stripe of film-forming substance. An application roll, 63, is shown mounted on a shaft 64 journaled on the side frames of the machine. A lower roll 65 on a shaft 66 is shown as turning in a pan or reservoir 67 of the film-forming substance. A doctor or blade 68 controls the thickness of the layer of film-forming substance on the roll 65. In the apparatus shown in Figure 1 and detailed in Figure 4, it will be evident that the roll 63 picks up a layer of the coating substance from the lower roll 65 in the intervals between the passage of the bag tubes 69 so that as a bag tube passes between the rollers, a film of the sealing substance is applied to it on both sides in an area including the lines of weakening. Such a stripe of film-forming substance is shown at 70 in Figure 1.

The film-forming substance is preferably one which sets rapidly into a continuous, tough film. For this purpose, a thermoplastic sealing substance, applied hot, is preferable. There are many such substances which may be used, and I give below an example of one in an exemplary but not a limiting sense. The general characteristics of the film have been mentioned above.

50% paraffin wax (132° M. P.)

50% micro-crystalline wax (Petrosene B—Socony Vacuum)

12% ester gum, (melting point 154°)

It will be understood that in Figure 4 a separate application of the film-forming substance may be made directly to the roll 63 from a separate pan of the substance and a transfer roll.

In Figure 2 I have shown an apparatus applied to the same type of machine for forming lines of weakening which extend diagonally across corner portions of the bag tube. This apparatus comprises a roll 71 mounted on a shaft 72 journaled on the side frames of the machine. On the roll there is a perforating device 73 extending at an angle to the axis of the shaft, as shown. Depending upon the timing of the shaft in relation to the travel of the bag tubes, there may be one or more of these perforating devices. They operate against a lower roll 74 on a shaft

similarly journaled and wide enough to serve as an anvil throughout the length of the diagonally arranged perforating device or devices. The bag tubes 69 are carried from this mechanism by the conveyor 58 to a coating or sealing mechanism comprising in this instance upper and lower rolls 75 and 76 on shafts 77 and 78 journaled in the side frames of the machine. Each such roll, as more clearly shown in Figure 5, has one or more raised, diagonally arranged printing surfaces, 79 or 80. These surfaces are arranged to be supplied with the sealing substance from rollers 81 and 82, turning in pans 83 and 84 of the sealing substance, through transfer rolls 85 and 86. Doctors or blades, 87 and 88, control the thickness of the line of sealing substance remaining on the rolls. The lines of perforation are thus coated with sealing substance, as indicated at 89 in Figure 2.

The lines of perforation formed in the bag tubes may be made before or after or concurrently with the formation of either of the end closure seams of the bag, and may be made at either or both ends of the bag tube. While I have illustrated in the drawings hereof right angle machines for treating unit length bag tubes, the skilled worker in the art in the light of these teachings will be readily able to adapt the mechanisms shown to the treatment of an endless length of bag tube as it is being delivered from a tubing device, as in Patents 2,099,257 and Re. 20,789. Perforating devices located axially or diagonally of rolls may be employed for this purpose as well as spot printing devices appropriately shaped to apply the stripes of sealing adhesive. It is also possible to treat a strip of bag forming web so as to provide appropriately spaced lines of weakening therein and so as to seal these lines by an application of film-forming sealing substance prior to the tubing of the strip. In such an operation, it is possible, if desired, to cause the stripe of sealing adhesive to be located inside the bag tube, as will be clear.

The lines of perforation and sealing films may be made across a preformed closure without impairing the closure. They may be made in bag walls prior to closure, and when so made will not interfere with the formation of the closure or the seal thereof. Where bag material is perforated or weakened prior to the formation of bag tubes and is then provided with the sealing films, the nature of the tubing operation becomes unimportant, and bellows-fold or intucked bag tubes may readily be made. Where bags or bag tubes are first made and then perforated, it is necessary to take precautions to insure that the sealing films cover the lines of perforation through their length. Hence it is most convenient to work on flat tubes or bags.

Where, as in Figure 2, the line or lines of weakening are disposed aslant to the major axis of the bag tube and run out to an end thereof, it is not important whether the bag tube be sealed at that end prior to the formation of lines of weakening and the covering thereof, as described, or whether the bag tubes shall be perforated and thereafter closed and sealed.

The machine sections shown in Figures 1 and 2 may be caused to deliver the bag tubes to apparatus for imposing them upon carton blanks and adhering them thereto, followed by the tubing of the carton blanks, as set forth in the patents to which reference has been made.

A bag tube 69 sealed at one end, as at 90, and having the sealed lines of weakening 70, is shown

in Figure 6 as imposed upon a carton blank 91. This particular blank is one shown in Patent 2,250,249 and is tubed by bending it along score lines intermediate the end walls of the carton. The bag tubes, however, may be applied to other types of carton and may be sealed at one end or open at both ends prior to such imposition. Figure 6 shows the application of adhesive, as at 92, so as to cause the bag or bag tube to adhere to the enclosing body walls of the carton, so that when the carton is squared up or erected, the bag or bag tube will likewise be squared up and opened at least on one end preparatory to filling. The lined carton 91 is shown in knocked down form in Figure 7. It will be erected, filled, the bag sealed, and the carton closed, as in the patents set forth above.

Figure 8 shows such a filled carton after it reaches the hands of the ultimate consumer and after he has opened the flaps 93 so as to disclose the filled bag 69. The next step, as indicated in Figure 9, is to pull upwardly upon the end closure seam 90 of the bag. A further upward pulling operation, accompanied by a twisting operation, as illustrated in Figure 10, will serve to cause the upper portion of the bag to sever from the lower portion along the weakened line formed therein which, in this case, is a continuous peripheral line substantially coinciding with the upper edges of the enclosing walls of the carton. The upper portion of the bag may be entirely removed, as shown in Figure 11, and after the removal of a portion of the contents 94 of the package, it may be reclosed by folding over the closure flaps 93.

Where the lines of weakening have been made as described in connection with Figure 2, the carton may first be opened, as shown in Figure 12, then the top of the bag raised or unfolded, as shown in Figure 13. The bag may then be torn along the lines of weakening 69 so as to remove a corner thereof, 95. This provides an opening in the bag through which a portion of the contents may be removed by pouring; and if the removed corner 95 of the bag is properly proportioned, sufficient of the upper parts of the bag walls will remain to permit a folding over of these bag wall portions and reclosure of the bag, as well as reclosure of the carton, as explained above.

It will be apparent that according to my invention, the nature of the material to be applied to seal up the perforations or line of severance can be adapted to the particular product to be packed within the liner or bag. In the case of lard, for example, it would be desirable to use some grease-resistant medium so there would be no leakage or seepage of the fat and so that the liner would retain its integrity and provide protection until the top is finally removed by the user, as illustrated. In the case of other products such as powders, the compound or sealing medium over the line of perforation should serve the primary purpose of retaining siftproofness, and in such an event, might be a material such as paraffin wax (or a resin modified paraffin, to overcome brittleness). In certain other cases, as for example, a flaky or granular content within the liner or bag, the use of any sealing medium at all may be unnecessary, in which case the perforating alone could be used, by-passing the unit which applied the sealing medium, although I prefer to use the sealing medium to provide the maximum possible protection of the contents. A sealing medium, such as described herein, properly applied and bonded

to walls of the bag will, however, provide protection against infiltration or loss of moisture, vapor and gases, where special gases are employed. As indicated, I may also color the sealing medium 5 some distinctive shade, such as bright red, for example, so that the line of tear is plainly and clearly marked, and this is another feature of my invention.

I have indicated that my invention is adapted 10 to use on separate bags as well as bags or liners within carton bodies, and this will now be readily apparent from the previous description. My opening means is particularly desirable and particularly advantageous for bags formed of materials which are difficult to tear and which are tightly sealed, such, for example, as a bag made 15 of rubber hydrochloride sheeting, such as Pliofilm laminated to paper. In such a laminated bag, the fused mouth is very difficult to open due to the bonding quality of the Pliofilm; and the rubbery 20 nature of the Pliofilm liner also makes it extremely difficult to tear such a bag open. By my invention, these problems are entirely eliminated, and at the same time through the use of the 25 proper sealing medium to cover over the perforation or line of severance, the essential protective characteristics of such Pliofilm lined bags can be fully retained, providing a protective bag or liner which can be readily and simply opened when desired.

It will be apparent that according to the adjustment of the machine, the line of severance can be placed in any predetermined, desired location, or at any desired angle to the bag or tube 30 itself. In Figure 9, the line of severance is placed substantially flush with the top of the outer carton but, if desired, this could be raised to the point where it was slightly under the sealed or folded closure of the bag, so that after the sealed 35 portion is torn off, there still remains sufficient extending material to be refolded over the surface of the contents. As shown in Figure 12, the line of severance, if preferred, may be placed at an angle or on the bias, so that only a corner or a 40 portion of the seal is removed by the user to provide a simple and effective means of pouring, rather than removing the entire sealed area; and this is a matter of choice, depending on the nature 45 of the product packed.

It will also be apparent from the foregoing that 50 my invention may be carried out at various stages in the manufacture of bags or tubes. Several of them have been illustrated in the drawings; but it will be readily apparent to those skilled in the 55 art that, if desired, my invention might be practiced by the incorporation of suitable devices after the formation of the web into a continuous tube but prior to severing it into bag lengths.

Variations are within the scope of my invention, 60 and it is not intended to limit the invention to the particular forms described, except as covered by the claims herein. By my invention, I have provided means whereby flexible bags or tubes, even if made of extremely durable material, can be 65 readily and easily opened by the user when desired, and I have further provided means whereby this can be achieved without sacrificing the inherent protective characteristics of the bag or liner itself, and have accomplished all this with 70 no separate manufacturing operation or labor cost. The invention is not limited to single-ply bags; and it may be applied also to coated bags, where the sealing substance may be the same as the coating, or a substance capable of bonding 75 firmly with it. Having thus described my inven-

tion in certain exemplary embodiments, what I claim as new and desire to secure by Letters Patent is:

1. A process of forming a sealable and openable composite package which comprises forming a bag tube from web materials, closing and sealing one end of said bag tube, forming in said bag tube transverse lines for severance adjacent but spaced from the closed end of said tube, coating said lines for severance with a thermoplastic sealing substance, forming a carton blank having a series of body walls in articulation and capable of forming a closed tube, said body walls having ends in alignment in said blank, other parts of said blank articulated to said body walls for forming end closures thereof, and depositing said pre-formed bag tube on said blank in such a way as to align said lines for severance with the aligned ends of the body walls of said blank, and tubing said blank about said bag tube with the interposition of adhesive between the body walls of said blank and said bag tube whereby to adhere said bag tube to said body walls.

2. A process of forming bags or liners which includes the steps of providing a flat bag tube having open ends, sealing one end of said tube transversely by adhering the walls thereof together across said end, forming lines of perforation in opposite wall portions of said tube, said lines starting at an edge of the bag at a point adjacent but spaced from said transversely sealed end and extending through said sealed end, and thereafter covering said lines for severance with a thermoplastic sealing substance.

3. A process of forming bags or liners which comprises the steps of providing a flat bag tube having open ends and lines of perforation in opposite wall portions of the tube, said lines starting at an edge of the bag at a point adjacent but spaced from an open end thereof and extending

slantwise to the longitudinal axis of the bag and intersecting the said open end intermediate its ends, sealing the said end of said tube transversely by adhering the walls thereof together across said end, and thereafter applying to said lines of perforation and adjacent portions of the tube walls a thermoplastic sealing substance.

4. A process of making bags or liners which includes the steps of conveying unit lengths of flexible flat bag tubes having open ends in a path of travel, sealing one end of said tubes transversely by adhering the walls thereof together across said ends, forming lines of perforation in opposite wall portions of said tubes, said lines starting at an edge of the bag tubes at a point adjacent but spaced from said transversely sealed ends and extending through said transversely sealed end intermediate the ends thereof, and thereafter applying to said lines of perforations and adjacent portions of the tube walls a thermoplastic sealing substance.
